UNITED STATES PATENT OFFICE.

RICHARD COLBERT MASON, OF TULSA, OKLAHOMA.

WELL-MEASURING APPARATUS.

Application filed April 14, 1922. Serial No. 552,719.

To all whom it may concern:

Be it known that I, RICHARD C. MASON, a citizen of the United States, and a resident of Tulsa, in the county of Tulsa and State of 5 Oklahoma, have made certain new and useful Improvements in Well-Measuring Apparatus, of which the following is a specification.

This invention relates to an improvement 10 in well measuring apparatus of the type embodying driving wheels coacting with the cable, or sand line, to accurately measure the depth of a well.

The object of the invention is to provide 15 an apparatus of this character wherein the driving wheels are positively constrained to partake of a motion corresponding to the motion of the cable, the cable being held in driving engagement with the driving wheels 20 at all times in order to effect this operation.

A further object is to provide an apparatus of this character with extremely simple and yet efficient and positively acting means for constraining the driving wheels 25 to partake of motion in the same degree and in the same direction.

Another object is to provide a device of 30 this character which is of a simple and durable construction, reliable in operation and easy and inexpensive to manufacture.

Other objects and advantages reside in certain novel features of construction, combination and arrangement of parts, which will be hereinafter more fully described, and 35 particularly pointed out in the appended claims, reference being had to the accompanying drawing forming part of this specification, and in which:

Figure 1 is a view in side elevation illustrating the preferred embodiment of the 40 invention, parts being broken away and parts being shown in section for the sake of illustration, and,

Figure 2 is a view in transverse horizontal 45 section on line 2-2 of Fig. 1, parts being shown in elevation for the sake of illustration.

Referring to the drawings, wherein, for 50 the sake of illustration is shown the preferred embodiment of the invention, the sand line or cable which is adapted to extend down into the well is designated at C, and the apparatus which measures this sand line or cable and which consequently measures the depth of the well is indicated generally at M and is adapted to be mounted

upon the upper end of the well casing or the like.

This well measuring apparatus comprises a main frame designated generally at 10 and 60 preferably constructed of metal, the main frame including sides 11 and 12 having reinforcing ribs 13 and 14, respectively, a bottom 15 and a top 16, the bottom and the top being of relatively heavy construction, as 65 clearly shown in the drawings. The side 11 consists of a straight bar of metal curved at its ends into the top and bottom and the side 12 consists of two sections 12^a and 12^b angularly arranged with respect to each 70 other. The bottom 15 and top 16 are provided with U-shaped openings 17 and 18 respectively, through which the sand line or cable C extends when the device is in use. 75

The bottom 15 and the top 16 of the frame are provided with seats or notches indicated at 19 in which longitudinal bars 21 are seated, the bars being secured to the frame by bolts and nuts 23. 80

Driving wheels 25, 26 and 27 are arranged between a pair of the bars 21 and are mounted upon axles 28, 29 and 30 respectively, the driving wheels 25 and 27 being loosely mounted on the axles 28 and 30 and the 85 driving wheel 26 being fixed to the axle 29. The driving wheels directly engage the sand line or cable and receive the motion thereof.

Means is provided for constraining the 90 driving wheels to corresponding motion and this means preferably comprises disks 31, 32, and 33 secured to the driving wheels 25, 26 and 27, respectively, and arranged eccentrically of the shaft or axle to which the driving wheels are respectively secured, as 95 clearly shown in Figure 1, the disks 31, 32 and 33 thus constituting eccentrics.

An eccentric strap 35 coacts with the eccentric disks 31, 32 and 33, and for this 100 purpose it includes an annular portion or ring 36, for each of the disks, the annular portions or rings encircling the disks. Ball bearings or other anti-friction means such as designated at 37 are interposed between the periphery of the eccentric disks and the inner periphery of the annular portions or rings. If desired, the disks or the annular portions may embody a removable retaining ring having threaded connection therewith so as to facilitate the assembly of the balls 105 in the races provided therefor in the pe- 110

iphery of the eccentric disks and of the annular ring portion.

The axle 29 extends for a substantial distance beyond the bar 21 in which it is journaled, and is adapted to be connected to a register or other suitable device for indicating the measurements taken. Between the register R and the bar 22 a brass disk 40 is fixed to the axle 29 and bears the indicia shown in the drawings, the indicia being designated at 40^a and representing inches.

A tensioning device coacts with the driving wheels and includes a screw threaded shaft 41, operatively mounted in a threaded bearing 42 provided therefor in the side 12 of the main frame. At its outer end the screw shaft 41 has connected thereto an operating handle 43 and between the operating handle and the threaded bearing a locking device 44 is provided and has threaded connection with the screw and is engageable with the threaded bearing to releasably secure the shaft in any position to which it may be adjusted. The inner end of the screw shaft carries a tension block 45, the tension block being connected to the screw shaft by means of a swivel connection 46. Adjacent the swivel connection 46 the block 45 is hollowed out to provide a cavity 47 and in this cavity a compression coil spring 48 is arranged and abuts the bottom of the cavity at one end and a brass cup 49 at its opposite end, the brass cup engaging the ball of the swivel connection as clearly shown in the drawings.

At its ends the block 45 is bifurcated to receive tension rollers 50 rotatably mounted on pintles 57 carried by the bifurcated portions of the block. If desired, the tension rollers may be provided with peripheral grooves to better engage the cable or sand line. It is to be understood also that the driving wheels may or may not be provided with peripheral grooves as desired. Tension block 45 operates between a pair of bars 21 which serve as guides for the tension block and prevent lateral displacement thereof.

In operation the well measuring apparatus is positioned on the well casing and the driving wheels and the tension rollers are engaged with the cable or sand line. The length of the sand line and consequently the depth of the well is thus accurately measured since the driving wheels are held in positive engagement with the sand line and move in correspondence therewith at all times. The accuracy of the measurement thus obtained is due in a large meas-

ure to the fact that the driving wheels are positively constrained to partake of motion in the same degree by virtue of the action of the eccentric disks and the eccentric strap. Moreover, in view of the interposition of the ball bearing the disk and strap operate to constrain the wheels to partake of corresponding motion with maximum efficiency, whereby the tendency of the cable or sand line to slip by the wheels is reduced to a minimum and this especially in view of the action of the tensioning device.

The register serves to indicate measurements made by the device and the brass disk indicates the increments in inches to be added to the measurements indicated by the register.

I claim:

1. In a well measuring apparatus, a frame, a plurality of axles rotatably mounted in the frame, driving wheels mounted on the axles, 80 disks fixed to said driving wheels eccentrically thereof, and an eccentric strap coacting with the disks.

2. In a well measuring apparatus, a frame, a plurality of axles rotatably mounted in the frame, driving wheels mounted on the axle, disks fixed to said driving wheels eccentrically thereof, an eccentric strap coacting with the disks, and ball bearings between the eccentric strap and said 90 disks.

3. In a well measuring apparatus, a frame, driving wheels carried by the frame, means for constraining said driving wheels to corresponding motion, a register driven from one of the driving wheels and indicating measurements made by the device, and a disk fixed to the driving wheels from which the register is driven and bearing indicia to indicate the increments to be 100 added to the measurements of the register.

4. In a well measuring apparatus, a frame including sides, top and bottom, a pair of bars secured to said top and bottom, said top and bottom having U-shaped openings vertically aligned and opening to one side of the frame, said U-shaped openings being adapted to accommodate a sand line, a plurality of axles supported upon said bars, driving wheels mounted on said axles 110 and adapted to engage the sand line, a tensioning device for urging the sand line into engagement with the driving wheels, a disk fixed to each of said driving wheels eccentric thereof, and an eccentric strap coacting with 115 said disks.

RICHARD COLBERT MASON.
